UNITED STATES PATENT OFFICE.

ALBERT CHARLES JAMES GUÉNÉE, OF FONTENAY SOUS BOIS, FRANCE.

ELECTROPNEUMATIC HAMMER.

Application filed September 30, 1924, Serial No. 740,851, and in France October 6, 1923.

The present invention relates to an electro-pneumatic hammer in which the movable element or striker serving to produce the impact is actuated in the direction of the work by compressed air, or more generally by the expansion of a compressed gas or vapour, or any suitable fluid under pressure, and is brought back by the action of an electro-magnet, the heat which is lost in the electro-magnet being utilized for heating the air or gas when entering the power cylinder.

The valve gear for the compressed air supply comprises two arrangements, one for the admission and a second for the discharge, these being independent of each other and each controlled by an electro-magnet. For the sake of simplicity, the said valve gear comprises ordinary slide valves controlled by reaction springs.

The striker may also be brought back by the electro-magnet controlling the discharge valve, provided the said striker opens the gas outlet ports somewhat before the end of its stroke; in this manner the electro-magnet will only come into action to bring back the striker after the impact has taken place, and therefore will not diminish the intensity of the latter.

In order to avoid all causes of damage to the apparatus should the striker be operated when the tool is out of contact with the work, the impact in the present device is not produced directly upon the head of the tool, but upon an intermediate element or anvil which is slidable in the axial direction and is provided with an apertured flange. When the said anvil is not driven back by the thrust upon the tool, it closes the orifices by which the air may escape during the descent of the striker, and an air cushion will thus be formed below the said anvil by which the shock will be absorbed.

The hammer is actuated by a motor of any suitable kind, hydraulic, electric or thermic, which serves to operate an alternator as well as an air compressor.

The said alternator is of the self-excited type and supplies alternating current to the electro-magnets of the hammer through the medium of a rotatable switch, and it comprises continuous current winding which on the one hand furnishes the exciting current and on the other hand supplies current for the control of an electro-magnetic clutch which will be hereinafter specified.

The frequency of the alternator should exceed that of the hammer, so that each electro-magnet may be energized, in the proper conditions as regards opening and closing the circuit; the ratio between the frequency of the alternating current and the frequency of the shocks produced by the striker is an integer in the present case.

The said compressor is actuated by the motor through the medium of an electro-magnet clutch, and it delivers compressed air into suitable storage tanks; when the pressure in the latter becomes sufficient, a pressure regulator will operate in order to break the circuit of the said clutch.

It may prove advisable in cases in which the hammer is required to operate only in an intermittent manner, for example in riveting work, that the compressor should be put in action only during the stopping periods of the motor. The compressor can be stopped by breaking the circuit of the said clutch when the hammer is set in operation.

The current passes through the said rotatable switch and then into a small switch which is mounted upon the handle of the tool. In order to reduce the power of the hammer, and chiefly when starting, the latter switch may be so devised that it will close the circuit of the electro-magnets through one or more resistances, then short-circuiting the latter.

Obviously, a motor such as described may supply power to various hammers, this depending solely upon the size and power of the said motor relative to the number of hammers employed.

The appended drawing shows by way of example an embodiment of the said invention.

Fig. 1 is a general view of the hammer, partly in elevation and partly in section.

Fig. 2 shows the control device of the hammer.

Fig. 3 is a voltage diagram showing the manner in which the various periods of the alternating current are utilized to energize the electro-magnet.

Fig. 4 shows the arrangement of the circuits for the valve gear.

The said hammer, Fig. 1, essentially comprises a main body 1 consisting of various parts, upon which is disposed the operating handle 2. The cylinder 3 is coaxial with the said body and has movable therein the

piston or striker 4, said cylinder communicating at the top with the compressed air inlet 5. The admission of the said air into the cylinder 3 is controlled by a slide-valve 6 which is pierced with the apertures or ports 7 and moves in co-operation with a stationary wall 8 having therein the ports 9. An electro-magnet 10 controls the opening of the said valve, the same being closed 10 by the spring 11.

The exhaust slide valve consists of the pole-piece 12 of an electro-magnet 13, which serves to regulate the effort exercised by the latter; the said valve moves in front of the ports 14 provided in the wall of the cylinder 3 and connects them with the ports 15 pierced in the external wall of the said main body of the apparatus. The slide valve 12 is urged by the reaction spring 16 which maintains it normally in the position in which the ports 14 are closed. 20

The ports 17 are formed in the wall of the cylinder 3 somewhat above the position occupied by the striker 4 when at the bottom of the stroke. Below the cylinder 3 is screwed a stationary sleeve 18 pierced with orifices 19 communicating with the atmosphere. Within the said sleeve is freely slideable within certain limits a co-operating member or anvil 20 which is pierced with the longitudinal ducts 21 and is adapted to enter into contact with the said striker, whose motion it imparts to the tool. Below the handle 2 is disposed a switching device shown 30 diagrammatically at 22 and controlled by the lever 23.

The operation is as follows:

When the said striker is accurately disposed upon the piece of work, the thrust exercised thereon through the medium of the tool will cause the said anvil to assume the upper position, Fig. 1, and the air which has passed under the striker along the walls thereof which are, of course, not air-tight 40 can escape through the orifices 21 and 19. This being the case, the switch 22 being placed in the position corresponding to the operation of the apparatus, whilst the striker is supposed to be at the upper end of the 45 stroke, current is sent into the electro-magnet 10; the latter will upwardly attract the valve 6 and will bring the ports 7 in line with the ports 9. The compressed air now acts upon the said hammer which descends, 50 thus producing an impact upon the said anvil which imparts it to the tool. During this movement, since the electro-magnet 13 is not energized, the valve 12 will now be acted upon by its return spring 16 and will close 55 the exhaust orifices 14. The striker 4 is subject to a rebound, and upon attaining the lower end of the stroke, the air situated above the same will be discharged through the orifices 17. 60

At this moment the circuit of the electro-

magnet 10 having been previously broken the circuit of the electro-magnet 13 is closed. Under the action of the spring 11, the valve 6 resumes its initial position, thus closing the ports 9; the electro-magnet 13 attracts 70 both the said striker, which now rises, and the valve 12 which uncovers the ports 14, thus providing for the discharge of the air which has remained above the said striker. The movement is then continued in the same 75 cycle of operations.

Should the tool be no longer in contact with the piece of work the said anvil will fall by its own weight to its lower position; the ports 21 will be closed, and the air situated below the said striker, which is unable to escape will form a cushion absorbing the shocks produced if the hammer is improperly set in operation. 80

The motor supplying the said hammer 85 with electric current and compressed air is shown diagrammatically in Fig. 2; this motor 24 which is an electric motor in the example represented drives the alternator 25 by direct coupling. It also controls through the 90 electro-magnetic clutch 26 and the gearing 27, the air compressor 28; the air delivered by the latter is stored in the tanks 29, 29', and a pressure regulator 30 effects the clutching at 26 when the pressure in said tanks attains a certain value. The clutch 26 is as above 95 stated supplied with current from a shunt circuit upon the exciter armature of the alternator. The alternating current required for the electro-magnets 10 and 13 of the hammer is supplied to the latter through the rotatable switch 31, Fig. 4, which comprises an insulating disc 32 rotating on an axis 33 and provided on the one hand with a circular conducting ring 34 and on the other hand with two conducting sectors 35 and 36 which are situated at unequal distances from the centre. The said ring co-operates with a brush 37 which is connected by a wire 38 to one pole of the alternating current circuit of the alternator. The sectors 35 and 36 are in permanent electrical connection with the 100 said ring. 110

The brushes 39 and 40 co-operate respectively with the sectors 35 and 36, and are 115 connected on the one hand by the wires 41 and 42 to the two poles of the continuous current circuit of the alternator, and on the other hand respectively to the electro-magnets 10 and 13 by the wires 43 and 44. The 120 said electro-magnets are also connected to the switch 22, disposed upon the hammer, this being shown in Fig. 4; said switch comprises two contact pieces 45 and 46 which are on the one hand respectively connected to the wires 43 and 44 situated outwardly of the said electro-magnets; the switch also 125 comprises the contact piece 47 which is connected by the wire 48 with the second pole of the alternating current circuit of the al- 130

terminator. Co-operating with the contact piece 47 are two contact pieces 49 and 50 which are respectively connected by the wires 51 and 52 with the electro-magnets 10 and 13. A suitable resistance 53 is disposed between the wires 51 and 52. The said switch further comprises a movable contact piece 54 co-operating with the above-mentioned stationary contact pieces. The winding of 10 the electromagnetic clutch is inserted in wire 42; the pressure regulator 30 is adapted to open the circuit of wire 42 when the pressure in the compressor increases above a certain limit and the compressed air moves the piston 30' (Fig. 2) towards the right hand side of the figure against the action of its spring 30''. This movement of the piston 30 draws apart the contact parts 42' inserted in the wire 42.

20 The diagram (Fig. 3) shows in full lines the voltage curve and in dotted lines the current curve which, as illustrated, is 90° out of phase with the voltage curve. In the example shown the ratio between the frequencies of the alternator and the striker is 3. The current is allowed to flow between a maximum and a minimum of the voltage in order to provide for the intensity rising gradually to a maximum and then decreasing gradually. Between A and B, the current flows in the electro-magnet 10 which opens the inlet valve, and the air thus enters the cylinder; the circuit is broken after the point B; the striker continues upon its stroke 25 and the air in the cylinder will thus expand. From C to D, the circuit of the electro-magnet 13 is closed, and the latter actuates the striker 4 and the discharge valve 12. The striker, after rebounding, will be brought to 30 the rear under the attraction of the electro-magnet 13. When the voltage is about to attain zero adjacent the point D, and consequently its intensity at a maximum, the valve 12 returns to the rear and closes the 35 discharge ports. A certain pressure will prevail above the striker 4 and will arrest its motion then at the point E the admission of air will recommence.

Fig. 4 is a general diagram of the electrically-operated valve gear.

50 If the switch 22 of the striker is in the inoperative position, i. e. if the movable contact member 54 connects together the contact pieces 45 and 46, no alternating current will be supplied, even when the contact segment 35 comes under the brush 39 or the segment 36 under the brush 40; however the continuous current will proceed through the wires 41 and 43, the contact piece 45, the 55 contact member 54, the contact piece 46, the wires 44 and 42, and the clutch 26. The air compressor 28 is thus connected to the motor 24 and supplies compressed air to the tanks 29, 29' the hammer being in the inoperative 60 position.

But if the movable contact member 54 of the switch 22 connects together the contact pieces 47 and 49, while the contact segment 36 comes under the brush 40, the alternating current will proceed through the wire 38, the brush 37, the ring 34, the contact segment 36, the brush 40, the wire 44, the electromagnet 13, the wire 52, the contact piece 49, the contact pieces 54 and 47, and the wire 48. The electro-magnet 13 will be thus energized and it thus brings back the striker 4 and attracts the valve 12. In like manner, when the segment 35 comes under the brush 39, the alternating current passes through the wire 38, the brush 37, the ring 34, the segment 35, 70 the brush 39, the wire 43, the electro-magnet 10, the wire 51, the resistance 53, the contact piece 49, the contact member 54, the contact piece 47 and the wire 48. Due to the resistance 53, the electro-magnet 10 will only partially open the inlet valve 6, so that the said striker will operate with diminished power.

75 During all these operations, the continuous current circuit remains broken and the compressor 28 is inoperative.

80 The movable contact member 54 may further connect together the contact pieces 49 and 50 and the contact piece 47. In this event, when the segment 35 comes under the brush 39, the current will proceed through the wire 38, the brush 37, the contact piece 35, the brush 39, the wire 43, the electro-magnet 10, the wire 51, the contact piece 50, the contact member 54, the contact piece 47 85 and the wire 48. The resistance 53 will now be short-circuited, and the electro-magnet 10 allows the full admission of the compressed air into the cylinder 3.

85 As above stated, the clutch 26 connecting the motor to the compressor has its circuit broken not only when the hammer is in operation, when 54 is between the contact parts 45 and 46 but also under the action of the pressure regulator 30 when the pressure becomes sufficient in the tanks 29, 29'.

90 The wires 43, 44 and 48 are brought to the hammers through the compressed air supply tube 5 and are connected to the internal wiring of the said electro-magnets and the switch 22 by movable contact plug and socket pieces, so that when the flexible tube is removed from the hammer, the wires are disconnected at the same time. The socket portions 55 of the said plug devices are attached to the wires within the said tube in order to reduce the danger of short-circuiting to a minimum should the generator be improperly put in operation. The wires secured to the plugs 56 are connected to double insulated terminals traversing a plate in insulating material 57 so as to allow their airtight passage from the compressed air inlet chamber 5 to the terminals of the switch 22 and back again to the chamber 5 and the 95

wires proceeding to the electro-magnets are also brought out by means of double insulated terminals.

Obviously, the various details of construction as above set forth are given solely by way of example and are susceptible of numerous modifications without departing from the principle of the invention.

What I claim is:

16 1. An electropneumatic hammer comprising a cylinder, a striker sliding in said cylinder, a compressed air chamber above said cylinder, means for feeding air into said chamber, a series of ports connecting the compressed air chamber with the cylinder, a closing device for these ports, an electromagnet controlling said closing device, a series of exhaust ports for the compressed air in the wall of the cylinder, a second closing device for these exhaust ports, a second electromagnet controlling said second closing device and an alternator supplying current to both electromagnets.

25 2. An electropneumatic hammer comprising a cylinder, a striker sliding in said cylinder, a compressed air chamber above said cylinder, means for feeding air into said chamber, a series of ports connecting the compressed air chamber with the cylinder, a closing device for these ports, an electromagnet controlling said closing device, a series of exhaust ports for the compressed air in the wall of the cylinder, a second closing device for these exhaust ports, a second electromagnet controlling said second closing device and adapted to control the return movement of the striker and an alternator supplying current to both electromagnets.

39 3. An electropneumatic hammer comprising a cylinder, a striker sliding in said cylinder, a compressed air chamber above said cylinder, means for feeding air into said chamber, a series of ports connecting the compressed air chamber with the cylinder, a closing device for these ports, an electromagnet controlling the said closing device, a series of exhaust ports for the compressed air in the wall of the cylinder, a second closing device for these exhaust ports, a second electromagnet controlling the said second closing device and adapted to control the return movement of the striker, a second series of exhaust ports above lowest position of the striker and an alternator supplying current to both electromagnets.

45 4. An electropneumatic hammer comprising a cylinder, a striker sliding in said cylinder, a compressed air chamber above said cylinder, means for feeding air into said chamber, a series of ports connecting the compressed air chamber with the cylinder, a slide valve for these ports, reaction springs holding said valve closed, an electromagnet adapted to open said valve, a series of exhaust ports for the compressed air in the

wall of the cylinder, a second slide valve for these exhaust ports, a spring device holding said second slide valve closed, a second electromagnet controlling last mentioned valve and adapted to provide for the return movement of the striker after the impact and an alternator supplying current to both electromagnets.

5. An electropneumatic hammer comprising a cylinder, a striker sliding in said cylinder, a compressed air chamber above said cylinder, means for feeding air into said chamber, a series of ports connecting the compressed air chamber with the cylinder, a slide valve for these ports, reaction springs holding said valve closed, an electromagnet adapted to open said valve, a series of exhaust ports for the compressed air in the wall of the cylinder, a second slide valve for these exhaust ports, a spring device holding said second slide valve closed, a second electromagnet controlling last mentioned valve, and adapted to provide for the return movement of the striker after the impact and an alternator supplying current to both electromagnets with alternating current the frequency of which is greater than that of the impacts.

6. An electropneumatic hammer comprising a cylinder, a striker sliding in said cylinder, a compressed air chamber, a series of ports connecting the compressed air chamber with the cylinder, a slide valve for these ports, reaction springs holding said valve closed, an electromagnet adapted to open said valve, a series of exhaust ports for the compressed air in the wall of the cylinder, a second slide valve for these exhaust ports, a spring device holding said second slide valve closed, a second electromagnet controlling last mentioned valve and adapted to provide for the return movement of the striker after the impact, an alternator supplying current to both electromagnets and a rotatable switch controlling the supply of alternating current.

7. An electropneumatic hammer comprising a cylinder, a striker sliding in said cylinder, a compressed air chamber above said cylinder, means for feeding air into said chamber, a series of ports connecting the compressed air chamber with the cylinder, a slide valve for these ports, reaction springs holding said valve closed, an electromagnet adapted to open said valve, a series of exhaust ports for the compressed air in the wall of the cylinder, a second slide valve for these exhaust ports, a spring device holding said second slide valve closed, a second electromagnet controlling last mentioned valve and adapted to provide for the return movement of the striker after the impact, a movable anvil under the striker, discharge orifices in the lower part of the cylinder connecting the lower surface of the striker with the atmos-

phere and closed by the anvil when latter is at its lower position and an alternator supplying current to both electromagnets.

8. An electropneumatic hammer comprising a cylinder, a striker sliding in said cylinder, a compressed air chamber above said cylinder, a series of ports connecting the compressed air chamber with the cylinder, a slide valve for these ports, reaction springs holding said valve closed, an electromagnet adapted to open said valve, a series of exhaust ports for the compressed air in the wall of the cylinder, a second slide valve for these exhaust ports, a second series of springs holding said second slide valve closed, a second electromagnet controlling last mentioned valve and adapted to provide for the return movement of the striker after the impact, a compressor, a flexible conduit connecting the compressor with the compressed air chamber, an alternator supplying current to both electromagnets, a motor actuating the alternator and the compressor, an electromagnetic clutch fed by the alternator for connecting the compressor with the motor, and means for controlling the electric connection between the alternator and the electromagnetic clutch.

15 40 45 50 55 60 65 70 75

9. An electropneumatic hammer comprising a cylinder, a striker sliding in said cylinder, a compressed air chamber above said cylinder, means for feeding air into said chamber, a series of ports connecting the compressed air chamber with the cylinder, a slide valve for these ports, reaction springs holding said valve closed, an electromagnet adapted to open said valve, a series of exhaust ports for the compressed air in the wall of the cylinder, a second slide valve for these exhaust ports, a spring device holding said second slide valve closed, a second electromagnet controlling last mentioned valve and adapted to provide for the return movement of the striker after the impact, a compressor, a flexible conduit connecting the compressor with the compressed air chamber, an alternator supplying current to both electromagnets, a motor actuating the alternator and the compressor, an electromagnetic clutch fed by the alternator for connecting the compressor with the motor, and a switch connecting the alternator in one position with the electromagnets and in another with the electromagnetic clutch.

20 25 30 35 40 45 50 55 60 65 70 75

10. An electropneumatic hammer comprising a cylinder, a striker sliding in said cylinder, a compressed air chamber above said cylinder, a series of ports connecting the compressed air chamber with the cylinder, a slide valve for these ports, reaction springs holding said valve closed, an electromagnet adapted to open said valve, a series of exhaust ports for the compressed air in the wall of the cylinder, a second slide valve for these exhaust ports, a second series of springs holding said second slide valve closed, a second electromagnet controlling last mentioned valve and adapted to provide for the return movement of the striker after the impact, a compressor, a flexible conduit connecting the compressor with the compressed air chamber, an alternator supplying current to both electromagnets, a motor actuating the alternator and the compressor, an electromagnetic clutch fed by the alternator for connecting the compressor with the motor, and a switch connecting the alternator in one position with the electromagnets and in another with the electromagnetic clutch.

these exhaust ports, a device holding said second slide valve closed, a second electromagnet controlling last mentioned valve and adapted to provide for the return movement of the striker after the impact, a compressor, a flexible conduit connecting the compressor with the compressed air chamber, an alternator supplying current to both electromagnets, a motor actuating the alternator and the compressor, an electromagnetic clutch fed by the alternator for connecting the compressor with the motor, and means for controlling the electric connection between the alternator and the electromagnetic clutch.

15 20 25 30 35 40 45 50 55 60 65 70 75

10. An electropneumatic hammer comprising a cylinder, a striker sliding in said cylinder, a compressed air chamber above said cylinder, means for feeding air into said chamber, a series of ports connecting the compressed air chamber with the cylinder, a slide valve for these ports, reaction springs holding said valve closed, an electromagnet adapted to open said valve, a series of exhaust ports for the compressed air in the wall of the cylinder, a second slide valve for these exhaust ports, a spring device holding said second slide valve closed, a second electromagnet controlling last mentioned valve and adapted to provide for the return movement of the striker after the impact, resistance coils adapted to be inserted in the circuit of the electromagnet first mentioned and an alternator supplying current to both electromagnets.

In witness whereof I have hereunto set my hand.

ALBERT CHARLES JAMES GUÉNÉE.
